CLAIM

The ornamental design for footwear accessory, as shown and described.

DESCRIPTION

FIG. 1 is a top perspective view of the footwear accessory, showing my new design;

FIG. 2 is a front elevational view thereof;

FIG. 3 is a left side elevational view thereof;

FIG. 4 is a right side elevational view thereof; and,

FIG. 5 is a rear elevational view thereof.

The broken lines in FIGS. 1-5 are for illustrative purposes only and form no part of the claimed design.
